Primary Examiner — Abraham Bahta*(74) Attorney, Agent, or Firm* — Finnegan, Henderson, Farabow, Garrett & Dunner LLP(57) **CLAIM**

The ornamental design for a payment card, as shown and described.

DESCRIPTION

FIG. 1 is a front right perspective view of a payment card showing my new design;

FIG. 2 is a rear left perspective view thereof;

FIG. 3 is a front elevation view thereof;

FIG. 4 is a rear elevation view thereof;

FIG. 5 is a top plan view thereof, the bottom view being a mirror image thereof;

FIG. 6 is a right side view thereof;

FIG. 7 is a left side view thereof; and,

FIG. 8 is an enlarged, detailed view of the top view, as shown in FIG. 5.

The shape of the edge of the payment card illustrated in FIG. 8 is consistent around the perimeter of the top, right, left, and bottom sides of the payment card in both embodiments. Surface reflections form no part of the claimed design.
